TETHERED RING TOY

Filed Sept. 3, 1947

UNITED STATES PATENT OFFICE

2,506,453

TETHERED RING TOY

Paul S. Hinkle and Roland A. Hammer,
Detroit, Mich.

Application September 3, 1947, Serial No. 771,851

1 Claim. (Cl. 273—99)

1

Our invention relates to a game-toy.

More particularly it relates to a toy whereby a computing game may be played by impaling upon a peg, a ring suspended by a flexible member, such as a cord.

The principal object of our invention is to provide a toy of the swinging ring and peg type which may be manipulated by one hand to play a computing game in which the amount of the score is dependent upon skill.

Other objects and advantages will hereinafter appear.

The preferred embodiment of our invention is illustrated upon the accompanying drawing, wherein:

Fig. 1 is a side elevation of the complete toy; and

Fig. 2 is a small scale perspective illustrative of how the toy may be manipulated by one hand to play a computing game.

The toy comprises a body portion 5, which, to afford novelty and attractiveness to children, is shaped and decorated to simulate a clown's head in silhouette. Preferably the two sides are marked or printed to represent obverse sides of the head. The body may, however, be made of any desired shape. Preferably it should be made sufficiently large to prevent the ring from passing thereover.

A handle 6 projects from one side of body portion 5 and a pin or peg 7 projects from the body's opposite side. In the embodiment shown, the peg projects as a grotesque nose from the face of the head shaped body. The upper edge of the nose-shaped projecting peg is provided with a series of notches 8, each notch being designated by a counting number as shown. Since experience has demonstrated that the difficulty of placing the impaled ring upon a particular location along the peg increases with the distance from the body portion, we prefer that the notch designating numbers increase in value from the body toward the tip of the peg.

A ring 10 is attached to the body portion 5 by a flexible member 11, such as a cord or chain. The location of the attachment of cord 11 is relatively immaterial but we prefer to attach it through a hole in a part of the body which simulates a tongue. The cord should be longer than the distance from its attachment to the body to the tip of peg 7, preferably several times that length so as to afford a good free swing for the ring.

The body portion 5, handle 6 and peg 7 may be made in various shapes and of different materials. We prefer to form them all in one piece from a rather thin but rigid piece of cardboard

2

or wood. Ring 10 may be made of like material. The desired markings and coloring for opposite sides of the body portion, handle and peg may be directly applied or put upon paper, or other appropriate material and pasted to the sides of the cardboard or wood base.

A computing game may be played with the toy by grasping the handle in one hand, swinging the ring by its cord forwardly and upwardly, and by 10 varying the ring movement and manipulating the position and angle of the peg, trying to impale the ring upon the peg. The number of "trys" may be limited as desired, and the score of different players computed by adding the amounts represented by the notch designating numbers where the ring rests for each of the several attempts.

Having illustrated and described an embodiment and the nature of our invention, what we claim and desire to secure by United States Letters Patent is as follows:

A computing game-toy comprising a manually manipulatable body portion having a rigid handle and a rigid peg projecting from opposite sides thereof, the handle to be grasped in the player's hand to facilitate manipulating the body portion and peg, and the peg having a series of spaced notches therealong, each notch extending across the top surface of the peg and having a different numerical denomination from the other notches; 30 a ring having a hole therethrough larger than the peg so that it can be impaled thereon; and a flexible cord or the like attaching the ring to the body portion, the cord being of a length to permit the ring to be thrown a limited distance beyond the peg by manipulation through the handle of the body portion and by varying the throw of the ring and manipulation of the body portion enabling the player to intercept and catch the ring in different notches of the peg.
